UNITED STATES PATENT OFFICE

MAX HORA, OF DUSSELDORF-OBERKASSEL, GERMANY, ASSIGNOR TO THE FIRM EISENWERK UND MASCHINENBAU AKTIENGESELLSCHAFT, OF DUSSELDORF-HEERDT, GERMANY

PLATEN PRINTING PRESS

Application filed July 18, 1927, Serial No. 206,704, and in Germany July 21, 1926.

This invention relates to improvements in platen printing presses, and in particular to presses in which the platen reciprocates upon a flat track. In order to enable laying in and out to be effected quickly in platen presses of this kind, the arrangement is made according to the present invention that grippers fitted to chains circulate round the platen in such a manner that they move alternately in a direction in which they take the sheet off the laying-on table and place it in marks on the platen, then move in the opposite direction on to the sheet for the purpose of seizing it, and then move in the original direction again for the purpose of laying out the sheet. This alternating movement is produced by means of a novel driving mechanism for the chains of the grippers.

The grippers take the paper off a laying-on table which swings upwards each time, when a gripper moves through under it, and which swings downwards when a gripper moves on to it.

The sheets may be placed upon this table by hand, but for the purpose of quick laying on, an automatic pneumatic device is provided, which is connected with a device which raises the piling table upon which the sheets are stored according as the sheets are used up. This device is controlled by a feeler arm, which comes into contact with the uppermost sheet.

The platen press is furthermore also provided with a novel slide-way for the platen, which can be readily lubricated, without the lubricant being able to pass into the interior of the press, and which permits of adjustment for wear, the platen not being shifted sideways for such adjustment.

The invention is illustrated by way of example in the accompanying drawings, wherein—

Figure 1 is a perspective view of the platen press as a whole;

Figure 2 is a side elevation of the platen and of the gripper device in various positions, and of the device for driving the grippers;

Figure 3 a plan of the device for driving the grippers;

Figure 4 shows in plan the arrangement of the grippers on the chain;

Figure 5 shows the same arrangement in side elevation;

Figures 6, 7, 8 and 9 show the position of the grippers in the various successive positions of the platen shown in Figure 2;

Figure 10 shows the guide for the platen;

Figure 11 the same on a larger scale;

Figure 12 is a general view in perspective of the laying-on table;

Figure 13 a side elevation of the laying-on plate in a lowered position;

Figure 14 a side elevation of the same in a raised position;

Figure 15 a plan of the laying-on plate;

Figure 16 a side elevation of the laying-on marks of the laying-on plate on a larger scale;

Figure 17 a side elevation of the device for rocking the laying-on plate and for transferring the sheets thereto, and of the device for raising the piling table;

Figure 18 the same device seen from the right.

On a machine frame 1 the platen 2 reciprocates in guides 3, remaining at all times parallel to the forme 4. To the platen 2 are fitted on both sides supports 5, the lower ends 6 of which are constructed as three-sided prisms. With these it runs in accurately fitting V-shaped channels 7 (Figures 10 and 11), which are cut in the base of grooves 8 in rails 9, which prevent the lubricating oil from overflowing. On to the surface 10, which is left on the outside of the press beside the grooves 8, is screwed a rail 11, which engages in a groove 12 cut in the support 5, and bears upon the under side of the groove 12 so as to lock the support 5. The prism 6 is thus positively guided between the rail 11 and the channel 6.

In order to enable the positive guide to be adjusted for wear of the prism 6 and of the channel 7, the height of the surface 10 is so dimensioned as to leave between it and the rail 11 a gap, which is filled up by a number of very thin sheet-iron strips, not shown, of about from 0.1 to 0.2 millimetre in thickness. When an inadmissible amount of clearance space arises, owing to wear of the sliding

surfaces, between the rail 11 and the prism 6, one or more strips are taken away from below the rail 11 until the clearance space is equalized.

5 On each side of the platen 2 an endless chain 17 is passed round chain wheels 13, 14, 15 and 16, and upon each of these chains is arranged at two positions a number of grippers 18 and 19. The movable limbs of the 10 grippers are mounted upon a shaft 20 and are normally kept closed by a spring 21 coiled round the shaft, and only opened when a pawl 22 fitted to the end of the shaft 20 passes over a cam 38^a fixed at the position in question. In bearings 23 which are interposed in the chains 17 is journaled a shaft 24. The gripper shaft 20 is carried by arms 25 which are rigidly mounted upon the shaft 24. A spring 26 coiled round the shaft 24 tends to 15 rock the grippers into the position shown in dotted lines in Figure 5, but is prevented from doing so by a pawl 27, which engages in a recess in a collar 28 on the shaft 24.

To the shaft of the chain wheels 16 is slidably keyed a toothed wheel 29, the diameter of which is smaller than that of the chain wheels. The toothed wheel 29 moves in a frame 30, which is provided internally at the top and bottom with toothed racks 31 and 32. These engage one over the other in the manner illustrated in Figure 3, so that each rack occupies in the central part of the frame about half its breadth, and towards the end of the frame the whole of its breadth, and 20 that where one rack occupies the whole breadth of the frame the other is entirely absent. Furthermore at the two ends of the frame 30 are arranged triangular cams 33 and 34, which push the toothed wheel 29 over into the widened part of the corresponding rack.

When the platen 2 moves out of the printing position, shown in Figures 1 and 6, towards the right, the toothed wheel 29, mounted at the right-hand end of its shaft, first runs in the wide part of the lower rack 32, and the chain 17 moves in the direction of the arrow α in Figure 2. This however only continues until the toothed wheel 29 has reached 25 the position marked α in Figure 2, in which the lower rack 32 comes to an end on the right-hand side of the frame 30, and in which the toothed wheel 29 comes into engagement with the upper rack 31, as shown in Fig. 7. The 30 toothed wheel 29 then reverses its direction of rotation and the chain moves in the direction of the arrow γ , until the platen is completely opened. Upon the reversal of the platen the toothed wheel 29, which still meshes with the upper rack 31, again reverses its direction of movement, and the chain moves first in the direction of the arrow α (Fig. 8) until the toothed wheel enters at b 35 into the lower rack 32, whereupon the further movement of the chain then proceeds in the

direction of the arrow γ , until the platen has reached the printing position. Hence the result is that the endless chain 17, irrespectively of whether the platen is moving forward or backward, moves preferably in the direction γ , and only executes at the commencement of the opening and of the closing of the platen 2 a short backward movement each time in the direction α , and then immediately reverses into the direction γ again. Each time at the end of the movement α the seizing of the sheet is effected on the laying-on table or on the platen, and in the direction γ the laying in and out takes place.

The method of working of the apparatus is diagrammatically illustrated in Figures 6-9 inclusive. The corresponding positions of the platen are denoted in Figure 2 by V VI, VII and VIII respectively.

During the printing, the gripper 18 stands underneath the platen 2 in the neighbourhood of the register plate 36, and the gripper 19 above the platen in the neighbourhood of the rear side thereof. When the platen 2 begins its rearward movement of the forme 4, the grippers, so long as the toothed wheel 29 is in mesh with the rack 32, move in the direction α , and the gripper 18 seizes the lower edge of the sheet located on the platen. For this purpose it is opened as it approaches the sheet owing to the pawl 22 sliding over the cam 38^a. After the pawl 22 has passed over the cam 38^a the gripper again closes and in doing so seizes the sheet held between the marks and moves together therewith a short distance further upwards into the position VI in Figure 2 and in the position illustrated in Figure 7 its pawl 27 (Figure 5) strikes against a cam 38 mounted on the platen 2. This cam 38 is bevelled off and axially displaceable against the force of a spring (not shown) which presses it forward into the position shown in the drawings. When the gripper moves in the direction α to the register plate 36, its pawl 27 strikes against the cam 38 and is thereby rocked in the anticlockwise direction (shown in Figure 5 in dotted lines). By this means, the pawl 27 comes out of engagement with the ring 28, whereby the gripper shaft 20, under the force of the spring 26 as indicated in Figure 5 with dot and dash lines, swings away from the register plate 36 until a projection 39 on the ring 28 strikes against a stop 40 on the bearing 23. The grippers hereby swing so far away from the register plate 36 that the sheet, during its return movement, which now takes place, is lifted over the laying-on marks 41. As during its downward movement, the gripper is situated in the position shown in dot and dash lines in Figure 5, the pawl 22 does not strike against the cam 38^a, so that the gripper remains closed and holds the sheet securely. The position of the cam 38 on the platen is so dimensioned that in the case of smaller 45 50 55 60 65 70 75 80 85 90 95 100 105 110 115 120 125 130

sizes of paper the laying-on marks 41 can be fitted higher up than is shown in Figure 2, so that the printing is always effected in the centre of the platen. Since the grippers, owing to the swinging out, pass out of reach of the cam 38^a, by which they were opened when moving forward, they remain closed during the return movement, which now takes place in the direction of the arrow *y*. Their return is occasioned by the fact that the toothed wheel 29 now passes out of the widened part of the lower rack 32 into the rack 31, and reverses its direction of rotation. The gripper 18 takes with it the sheet that it has seized and brings it over a depositing table or turning rake 43, upon which it lets it fall as soon as its pawl 22 passes over a cam 44 mounted on the chain wheel 16, as shown in Fig. 8.

The gripper at this moment is still situated in the position shown in dotted lines in Figure 5. During the further movement of the gripper it passes below and along a stationary guide bar 48 fitted below the table 45 at such a distance from the chain 17 that the gripper comes into contact with the guide bar 48 and is thereby forced into the position shown in full lines in Figure 5, whereupon the pawl 27 again falls into the recess in the ring 28 and secures the gripper in this position. At the moment in which the sheet is to be deposited (Fig. 8), the toothed wheel 29 has reached the end of the rack 31, and the rearward movement of the platen now begins. Since the chain 17 at first reverses its direction of movement into the direction *x*, the gripper 19 which was located above the register plate 36 at the time of maximum opening of the platen, now passes on to the upper side of the platen and approaches the laying-on table 45. Upon the latter the sheet has been laid in a manner to be hereinafter described more fully, during the continuing of the earlier steps of the process, against marks 46 (Figure 9). At the moment of approach of the gripper 19 the laying-on table 45 is lowered by a device to be hereinafter described, so that the gripper 19 seizes the sheet at the edge. The pawl 22 passes over a cam wheel 47 (Figs. 2 and 9), which is only rotatable in the direction *y*, whereby the gripper is opened and immediately closes again, since the pawl 22 of the gripper must pass over the teeth of the wheel 47 which cannot rotate in this direction. During the closing of the gripper the sheet is seized. If, after this the gripper moves back in the direction *y* it is not opened again by the cam wheel 47, since the latter can turn in this direction of movement of the gripper and the pawl 22 can thus remain in a gap between the teeth of the wheel 47 and does not require to ride over the teeth of the wheel. At the same instant the toothed wheel 29 enters the lower rack 32, whereby the grippers 18 and 19 now moves in the direc-

tion of the arrow *y*, and the gripper 19 brings the gripped sheet on to the register plate 36. On the latter are laying-on marks 41, in which the gripper 19 lays the sheet. At the moment of its passage through the laying-on marks 41, the pawl 22 passes over a cam, not shown, owing to which the gripper 19 opens and leaves the sheet behind in the marks 41 (Fig. 2). The gripper 19 continues its movement beyond the marks 41, and at the end of this step of the work stands underneath the register plate 36 (Fig. 6), whence it moves against the sheet in the manner previously described during the return movement of the platen. Hence the gripper 19 now stands in the position which the gripper 18 previously occupied. At the termination of the next insertion of a sheet the gripper 18 again stands in this position.

The oscillatable laying-on table 45 is secured by means of a pivot 49 to a horizontal table 50, upon which the sheets are stacked. The parts 45 and 50 rest upon a frame 51, which can travel upon balls 52, and has a projection 53, by which it can be screwed firmly to the machine frame, as shown in Fig. 12.

For the raising and lowering of the laying-on table 45 there serves a bell-crank lever 54, with a roller 55, which is oscillatable about a stationary pivot 56. A rod 57 pivoted to the lower arm of the lever 54 is guided with a slot 58 upon the shaft 59 of a cam disc 60, upon the edge of which it bears, with a roller 61. When the roller 61 enters the notch in the cam disc, the laying-on plate sinks against the grippers 18 or 19. During the rest of the time the laying-on plate is raised, so that the grippers can pass through below it.

The laying-on plate may be provided, if the laying-on is being done by hand, with a belt conveyor 62, shown in Figs. 13 and 14, which runs over rollers 63 and 64, but this is not absolutely essential.

In front of the front edge of the laying-on plate 45 there is a stationary rail 65, upon which hook-shaped laying-on marks 46 are mounted. The latter are displaceable in grooves 66 in the rail 65. The laying-on marks are all screwed firmly to a rail 67, which carries stops 68 at both ends above the laying-on plate. The laying-on marks are in this manner, as shown in Fig. 16, raised during the upward swing of the laying-on plate 45 into the position shown in full lines. When the laying-on plate 45 swings downwards, the marks 46 descend with it as far as the position marked *a*, so that the sheet 69 is held fast during the descent of the marks. Then, when the laying-on plate descends right into its lowest position *b*, the marks 46 can no longer follow it, as they remain suspended by their bent parts upon the rail 65, and the sheet is accordingly released for removal by the grippers.

The method of working of the apparatus is as follows:—

While one gripper 18 or 19 during its forward movement indicated by an arrow passes through underneath the laying-on plate 69, the latter is brought by the cam disc 60 into its raised position, so that it does not hinder the passage of the gripper (Fig. 14). After the gripper 18 or 19 has reached approximately the position shown in dotted lines in Figure 14, it reverses its direction of movement and moves in the direction of the upwardly pointing arrow against the laying-on plate. The latter is at the same time lowered by the cam disc 60 (Fig. 13), so that the grippers, which then enter notches 70 in the laying-on plate, can seize the sheet. The lowest position which the laying-on plate assumes under these circumstances corresponds to the position *b* in Figure 16, so that in this way the sheet 60, which until then was guided on the marks 68, is only released at the moment at which the grippers seize it. Immediately after the grippers have pulled the sheet away under the marks 68 in the direction of the arrow, the laying-on plate 69 swings up again, so that the marks 46 can again arrive in front of its front edge (Fig. 14), and a new sheet 69 can be laid on. As the shape of the cam disc 60 shows, more than three-quarters of the time of one working stroke of the press is available for the laying-on.

A quicker working of the platen press is effected by laying on by means of a pneumatic device, as illustrated in Figures 17 and 18. In the case of this device, upon a shaft 73, which revolves once in the direction of the arrow during each working stroke, is mounted an eccentric disc 74, which by its rotation moves a connecting rod 75. The rod 75, with a lateral roller 76, runs upon the edge of the disc 74, and is lifted by the latter in the manner indicated in dotted lines. The return movement is effected by a spring 77. The rod 75 is pivoted to an arm 78 on a shaft 79, so that the latter is set in reciprocating movement.

At the two ends of the shaft 79 are mounted double levers 80, each with one approximately horizontal, and one upwardly directed arm, which serve for guiding suction rod holders 81. The suction rod holder 81 on each side, which carries at the upper end the suction rod 82, with the nozzles 83, is of angular shape and in the neighborhood of the apex thereof is pivoted by a bolt 84 to the horizontal arm of the lever 80. On its shorter arm, which engages under the arm 80, there is a positioning screw 85.

The upwardly pointing forked arm of the bell-crank lever 80 carries in a slotted bearing 86 a guiding piece 87. In the latter is slidably arranged a pressure bolt 88, which is pressed against the suction rod holder 81

by a spring 90 bearing at one end upon the guiding piece 87, and at the other end against a collar 89 on the pressure bolt.

The suction rod 82 slides on a stationary vertical guide 91, and therefore moves vertically upwards, with its nozzles, when it is raised by the lever 80, as far as the adjustment of the screw 85 permits. As soon as the screw 85 strikes against the arm 80, the suction rod holder 81 participates in the swinging movement of the lever 80, and the suction rod 82 then moves, with the gripped sheet of paper, upon the arcuate part of the line 82^a. At the end of this movement the nozzles push the sheet over a revolving feed roller 93, above which are located beating rollers 95 on oscillating levers 94. These beating rollers descend each time, after the release of the sheet, and press the latter against the roller 93, whereupon it is conveyed by the latter and by belt conveyors 97 running over rollers 96 to the laying-on mark 66, shown in Figure 16. Upon the shaft 79, beside the double lever 80, is mounted a lever 99, to the end of which is pivoted a tension rod 100, which is hooked at the other end. This tension rod is pivotally connected by means of a bolt 103 with a lever 102, which is rotatable upon a shaft 101. The tension lever 100 is intended to effect the transporting of the piling table together with the moving of the suction rod. The raising of the piling table 104 is effected when a ratchet wheel 105 mounted upon a shaft 101 is fed forward by a rocking lever 106 mounted loose on the shaft 101, and a pawl 107 pivoted to the said lever, through the medium of bevel gear wheels 108 and 109 and a screw 110. The arm 106 is then driven each time by the arm 102 in its oscillating movement, if a two-armed lever 111 rotatably mounted thereon passes with one of its arms under the hook of the link rod 100.

That arm of the double lever 111, which is on the left-hand side in Figure 17, is located in its dotted position under a connecting rod 112, which is guided with a slot 113 on a pin 114. Above the pile of paper, on a lever 115 of a shaft 116 there is a feeler roller 117. An arm 118 mounted on the end of the shaft 116 is pivotally connected with the rod 112. To the rod 112 is attached, by a slot 120 guided upon a pin 119, an oscillatably mounted double lever 121, which bears with a roller 122 against a cam disc 123 mounted upon a shaft 59. The roller 122 is pressed by the weight of the rod 112 against the cam disc 123. The latter executes one revolution during each working stroke of the machine. The rod 112 is hereby lowered each time until the feeler roller 117 bears upon the pile of sheets 124. So long as the pile of sheets 124 is sufficiently high for the removal of the paper by the suction rod, the rod 112, during the descent, only passes into

the position marked 112^a, in which it does not touch the double lever 111. Hence the latter remains stationary in that one of the two positions shown in dotted lines, in which 5 the hook 125 of the rod 100 passes over it during the return swing, without gripping it. The oscillating lever 106 therefore remains in the position shown in dotted lines. If however the pile of paper 124 has been so 10 far removed that the rod 112 passes right into the position 112^b, it rocks the double lever 111 into the position marked 111^a, in which it is seized by the returning hook 125 of the rod 100, and rocked into the position 15 shown in full lines. The arm 106 is hereby carried along with it, so that the pawl 107 actuates the ratchet wheel 105. This procedure is repeated until the feeler roller 117 of the rod 112 only permits of descent as far 20 as the position 117^a. The levers 111 and 106 are brought after each working step by a spring 127 back into their original positions, shown in dotted lines, in which they bear 25 against a stop 128.

25 What I claim is:—

1. A platen printing press, comprising a platen, grippers adapted to circulate round said platen, and means for causing said grippers to move alternately a short distance in 30 one direction and a longer distance in the opposite direction.

2. A platen printing press, comprising a platen, marks on said platen, a laying-on table, grippers adapted to circulate round 35 said platen, and means for causing said grippers to move alternately a short distance in one direction and a longer distance in the opposite direction, said grippers being adapted during their movement in one direction 40 to take a sheet of paper from the laying-on table and place it in the marks on the platen and during their return movement to seize said sheet again and lay it down.

3. A platen printing press, comprising a 45 platen, a shaft, a toothed driving wheel slidably mounted on said shaft and adapted to drive it, toothed chain wheels secured to said shaft, chains passing round said chain 50 wheels, grippers arranged on said chains and adapted to circulate round the platen, a lower rail, a toothed rack on the upper surface of 55 said lower rail, said rack occupying one side of the central part of said rail and extending across to the other side towards one end of 60 the rail, an upper rail parallel to said lower rail, a toothed rack on the under surface of 65 said upper rail, said second rack occupying one side of the central part of said upper rail facing the untoothed side of the central part 65 of the lower rail and extending across to the other side of its rail towards the end opposite to the end at which the first toothed rack extends across, both of said racks being adapted to mesh at different time with said toothed driving wheel which moves between them,

and cams adapted to slide said driving wheel along its shaft to transfer it from one side of the racks to the other when it reaches the ends of the rails.

4. A platen printing press, comprising a 70 platen, grippers adapted to circulate round said platen, means for causing said grippers to move alternately a short distance in one direction and a longer distance in the opposite direction, laying-on marks, and a 75 register plate, the grippers being adapted to lay a sheet of paper in said laying-on marks and leave it there, travel to a point outside the register plate, and return from there after the printing operation has been effected. 80

5. A platen printing press, comprising a 85 platen, a rod adapted to circulate round said platen, a gripper shaft oscillatably journaled on said rod, grippers secured to said gripper shaft, means for causing said grippers to move alternately a short distance in one direction and a longer distance in the opposite direction, and laying-on marks, said gripper shaft being adapted to rock away a sheet of paper that is to be laid out beyond 90 said laying-on marks after said sheet has been gripped.

6. A platen printing press, comprising a 95 platen, endless driving chains, grippers arranged on said chains and adapted to circulate round the platen, and means for causing said grippers to move alternately a short distance in one direction and a longer distance in the opposite direction, said grippers being adapted to lay down a sheet of paper immediately before the stoppage of the movement of the driving chains. 100

7. A platen printing press, comprising a 105 platen, grippers adapted to circulate round said platen, means for causing said grippers to move alternately a short distance in one direction and a longer distance in the opposite direction, and a laying-on plate, said laying-on plate being adapted to swing upwards while the grippers pass underneath it and to sink against the grippers when said grippers move on to the laying-on plate. 110

8. A platen printing press, comprising a 115 platen, grippers adapted to circulate round said platen, means for causing said grippers to move alternately a short distance in one direction and a longer distance in the opposite direction, a laying-on plate, said laying-on plate being adapted to swing upwards while the grippers pass underneath it and to sink against the grippers when said grippers move on to the laying-on plate, a stationary rail, fixed in front of the front edge of said laying-on plate, and laying-on marks so fitted to said stationary rail that they sink along with said laying-on plate and only release the front edge thereof, with the sheet of paper lying thereon, shortly before said laying-on plate reaches its lowest position. 120 125 130

9. A platen printing press, comprising a main frame, a standard, means such as casters fitted to the bottom of said standard to facilitate displacement thereof, means for securing said standard to the main frame, a platen, grippers adapted to circulate round said platen, means for causing said grippers to move alternately a short distance in one direction and a longer distance in the opposite direction, a horizontal table mounted on the standard, a laying-on plate, oscillatably mounted on said horizontal table, said laying-on plate being adapted to swing upwards while the grippers pass underneath it and to sink against the grippers when said grippers move on to the laying-on plate, a stationary rail, fixed in front of the front edge of said laying-on plate, laying-on marks so fitted to said stationary rail that they sink along with said laying-on plate and only release the front edge thereof, with the sheet of paper lying thereon, shortly before said laying-on plate reaches its lowest position.

10. A platen printing press, comprising a horizontal table, a laying-on plate, an oscillating suction rod adapted to feed sheets of paper automatically to said laying-on plate and horizontal table, holders for said suction rod, a guide for said suction rod, and swinging arms, said holders being resiliently pivoted to said swinging arms so as to keep said suction rod in contact with its guide during part of its oscillation.

11. A platen printing press, comprising a platen, grippers adapted to circulate round said platen, means for causing said grippers to move alternately a short distance in one direction and a longer distance in the opposite direction, a horizontal table, a laying-on plate, an oscillating suction rod adapted to feed sheets of paper automatically to said laying-on plate and horizontal table, holders for said suction rod, a guide for said suction rod, and swinging arms, said holders being resiliently pivoted to said swinging arms so as to keep said suction rod in contact with its guide during part of its oscillation.

12. A platen printing press, comprising a platen, grippers adapted to circulate round said platen, means for causing said grippers to move alternately a short distance in one direction and a longer distance in the opposite direction, a horizontal table, a laying-on plate, said laying-on plate being adapted to swing upwards while the grippers pass underneath it and to sink against the grippers when said grippers move on to the laying-on plate, an oscillating suction rod adapted to feed sheets of paper automatically to said laying-on plate and horizontal table, holders for said suction rod, a guide for said suction rod, and swinging arms, said holders being resiliently pivoted to said swinging arms so as to keep said suction rod in contact with its guide during part of its oscillation.

13. A platen printing press, comprising a platen, grippers adapted to circulate round said platen, means for causing said grippers to move alternately a short distance in one direction and a longer distance in the opposite direction, a horizontal table, a laying-on plate, said laying-on plate being adapted to swing upwards while the grippers pass underneath it and to sink against the grippers when said grippers move on to the laying-on plate, a stationary rail, fixed in front of the front edge of said laying-on plate, laying-on marks so fitted to said stationary rail that they sink along with said laying-on plate and only release the front edge thereof, with the sheet of paper lying thereon, shortly before said laying-on plate reaches its lowest position, an oscillating suction rod adapted to feed sheets of paper automatically to said laying-on plate and horizontal table, holders for said suction rod, a guide for said suction rod, and swinging arms, said holders being resiliently pivoted to said swinging arms so as to keep said suction rod in contact with its guide during part of its oscillation.

14. A platen printing press, comprising a main frame, a standard, means such as casters fitted to the bottom of said standard to facilitate displacement thereof, means for securing said standard to the main frame, a platen, grippers adapted to circulate round said platen, means for causing said grippers to move alternately a short distance in one direction and a longer distance in the opposite direction, a horizontal table mounted on the standard, a laying-on plate, oscillatably mounted on said horizontal table, said laying-on plate being adapted to swing upwards while the grippers pass underneath it and to sink against the grippers when said grippers move on to the laying-on plate, a stationary rail, fixed in front of the front edge of said laying-on plate, laying-on marks so fitted to said stationary rail that they sink along with said laying-on plate and only release the front edge thereof, with the sheet of paper lying thereon, shortly before said laying-on plate reaches its lowest position, an oscillating suction rod adapted to feed sheets of paper automatically to said laying-on plate and horizontal table, holders for said suction rod, a guide for said suction rod, and swinging arms, said holders being resiliently pivoted to said swinging arms so as to keep said suction rod in contact with its guide during part of its oscillation.

15. A platen printing press, comprising a horizontal table, a laying-on plate, an oscillating suction rod adapted to feed sheets of paper automatically to said laying-on plate and horizontal table, holders for said suction rod, a guide for said suction rod, swinging arms, said holders being pivoted to said swinging arms, resilient means interposed between said holders and said swinging arms

to press said suction rod against its guide during part of its oscillation, and an adjustable abutment adapted to limit the action of said resilient means so that the suction rod leaves its guide during part of its oscillation.

16. A platen printing press, comprising a platen, grippers adapted to circulate round said platen, means for causing said grippers to move alternately a short distance in one direction and a longer distance in the opposite direction, a horizontal table, a laying-on plate, an oscillating suction rod adapted to feed sheets of paper automatically to said laying-on plate and horizontal table, holders for said suction rod, a guide for said suction rod, swinging arms, said holders being pivoted to said swinging arms, resilient means interposed between said holders and said swinging arms to press said suction rod against its guide during part of its oscillation, and an adjustable abutment adapted to limit the action of said resilient means so that the suction rod leaves its guide during part of its oscillation.

17. A platen printing press, comprising a main frame, a standard, means such as casters fitted to the bottom of said standard to facilitate displacement thereof, means for securing said standard to the main frame, a platen, grippers adapted to circulate round said platen, means for causing said grippers to move alternately a short distance in one direction and a longer distance in the opposite direction, a horizontal table mounted on the standard, a laying-on plate, oscillatably mounted on said horizontal table, said laying-on plate being adapted to swing upwards while the grippers pass underneath it and to sink against the grippers when said grippers move on to the laying-on plate, a stationary rail, fixed in front of the front edge of said laying-on plate, laying-on marks so fitted to said stationary rail that they sink along with said laying-on plate and only release the front edge thereof, with the sheet of paper lying thereon, shortly before said laying-on plate reaches its lowest position, an oscillating suction rod adapted to feed sheets of paper automatically to said laying-on plate and horizontal table, holders for said suction rod, a guide for said suction rod, swinging arms, said holders being pivoted to said swinging arms, resilient means interposed between said holders and said swinging arms to press said suction rod against its guide during part of its oscillation, and an adjustable abutment adapted to limit the action of said resilient means so that the suction rod leaves its guide during part of its oscillation.

18. A platen printing press, comprising a horizontal table, a laying-on plate, an oscillating suction rod adapted to feed sheets of paper automatically to said laying-on plate and horizontal table, holders for said suction rod, a guide for said suction rod, swinging

arms, said holders being pivoted to said swinging arms, resilient means interposed between said holders and said swinging arms to press said suction rod against its guide during part of its oscillation, a table adapted to support a pile of sheets of paper, means for gradually raising said table as the pile of sheets thereon becomes smaller, and an eccentric adapted to actuate said table and also the suction rod holders.

19. A platen printing press, comprising a platen, grippers adapted to circulate round said platen, means for causing said grippers to move alternately a short distance in one direction and a longer distance in the opposite direction, a horizontal table, a laying-on plate, an oscillating suction rod adapted to feed sheets of paper automatically to said laying-on plate and horizontal table, holders for said suction rod, a guide for said suction rod, swinging arms, said holders being pivoted to said swinging arms, resilient means interposed between said holders and said swinging arms to press said suction rod against its guide during part of its oscillation, a table adapted to support a pile of sheets of paper, means for gradually raising said table as the pile of sheets thereon becomes smaller, and an eccentric adapted to actuate said table and also the suction rod holders.

20. A platen printing press, comprising a main frame, a standard, means such as casters fitted to the bottom of said standard to facilitate displacement thereof, means for securing said standard to the main frame, means for gradually raising said table as the pile of sheets thereon becomes smaller, a pivoted link rod, a hook at the end of said link rod, a lever adapted to reciprocate said link rod, a feeler device for feeling the height of the top of the pile of sheets, and a double lever, said feeler device being adapted to bring said link into engagement with the table raising means, by means of said double lever, when the top of the pile of sheets sinks below a predetermined level.

21. A platen printing press, comprising a platen, grippers adapted to circulate round said platen, means for causing said grippers to move alternately a short distance in one direction and a longer distance in the opposite direction, a main frame, a standard, means such as casters fitted to the bottom of said standard to facilitate displacement thereof, means for securing said standard to the main frame, means for gradually raising said table as the pile of sheets thereon becomes smaller, a pivoted link rod, a hook at the end of said link rod, a lever adapted to reciprocate said link rod, a feeler device for feeling the height of the top of the pile of sheets, and a double lever, said feeler device being adapted to bring said link into engagement with the table raising means, by means of said

double lever, when the top of the pile of sheets sinks below a predetermined level.

22. A platen printing press, comprising a platen, grippers adapted to circulate round said platen, means for causing said grippers to move alternately a short distance in one direction and a longer distance in the opposite direction, a horizontal table, a laying-on plate, an oscillating suction rod adapted to feed sheets of paper automatically to said laying-on plate and horizontal table, holders for said suction rod, a guide for said suction rod, swinging arms, said holders being pivoted to said swinging arms, resilient means interposed between said holders and said swinging arms to press said suction rod against its guide during part of its oscillation, a table adapted to support a pile of sheets of paper, means for gradually raising said table as the pile of sheets thereon becomes smaller, a pivoted link rod, a hook at the end of said link rod, a lever adapted to reciprocate said link rod, a feeler device for feeling the height of the top of the pile of sheets, a double lever, said feeler device being adapted to bring said link into engagement with the table raising means, by means of said double lever, when the top of the pile of sheets sinks below a predetermined level, and an eccentric adapted to actuate said table and also the suction rod holders.

23. A platen printing press, comprising a main frame, a forme supported on said main frame rails arranged on said main frame, said rails being formed with V-shaped grooves in their upper surfaces, standards V-shaped at their lower ends and adapted to run in said V-shaped grooves, and a platen supported by said standards.

24. A platen printing press, comprising a main frame, a forme supported on said main frame rails arranged on said main frame, said rails being formed with V-shaped grooves in their upper surfaces, standards V-shaped at their lower ends and adapted to run in said V-shaped grooves, a platen supported by said standards, grippers adapted to circulate round said platen, and means for causing said grippers to move alternately a short distance in one direction and a longer distance in the opposite direction.

25. A platen printing press, comprising a main frame, a forme supported on said main frame rails arranged on said main frame, said rails being formed with shallow troughs in their upper surfaces, and with V-shaped grooves in the bottoms of said troughs, standards V-shaped at their lower ends and adapted to run in said V-shaped grooves, towards and away from said forme, said troughs forming channels for lubricating oil between the sides of the V-shaped lower ends of the standards and the margins of the troughs, and a platen supported by said standards.

26. A platen printing press, comprising a

main frame, a forme supported on said main frame rails arranged on said main frame, said rails being formed with shallow troughs in their upper surfaces, and with V-shaped grooves in the bottoms of said troughs, standards V-shaped at their lower ends and adapted to run in said V-shaped grooves, towards and away from said forme, said troughs forming channels for lubricating oil between the sides of the V-shaped lower ends of the standards and the margins of the troughs, a platen supported by said standards, grippers adapted to circulate round said platen, and means for causing said grippers to move alternately a short distance in one direction and a longer distance in the opposite direction.

27. A platen printing press, comprising a main frame, a forme supported on said main frame rails arranged on said main frame, said rails being formed with V-shaped grooves in their upper surfaces, standards V-shaped at their lower ends and adapted to run in said V-shaped grooves, said standards being formed with grooves in one side, plates secured to the rails and adapted to engage with said side grooves, and means for adjusting the level of said plates to compensate for wear of the V-shaped grooves and of the V-shaped lower ends of the standards engaging therein, and a platen supported by said standards.

28. A platen printing press, comprising a main frame, a forme supported on said main frame rails arranged on said main frame, said rails being formed with V-shaped grooves in their upper surfaces, standards V-shaped at their lower ends and adapted to run in said V-shaped grooves, said standards being formed with grooves in one side, plates secured to the rails and adapted to engage with said side grooves, thin sheets removably inserted between said rails and said plates to enable the level of said plates to be adjusted to compensate for wear of the V-shaped grooves and of the V-shaped lower ends of the standards engaging therein, and a platen supported by said standards.

29. A platen printing press, comprising a main frame, a forme supported on said main frame rails arranged on said main frame, said rails being formed with shallow troughs in their upper surfaces and with V-shaped grooves in the bottoms of said troughs, standards V-shaped at their lower ends and adapted to run in said V-shaped grooves, towards and away from said forme, said troughs forming channels for lubricating oil between the sides of the V-shaped lower ends of the standards and the margins of the troughs, said standards being formed with grooves in one side, plates secured to the rails and adapted to engage with said side grooves, thin sheets removably inserted between said rails and said plates to enable the level of said

plates to be adjusted to compensate for wear of the V-shaped grooves and of the V-shaped lower ends of the standards engaging therein, and a platen supported by said standards.

5 30. A platen printing press, comprising a main frame, a forme supported on said main frame rails arranged on said main frame, said rails being formed with V-shaped grooves in their upper surfaces, standards V-shaped at their lower ends and adapted to run in said V-shaped grooves, said standards being formed with grooves in one side, plates secured to the rails and adapted to engage with said side grooves, thin sheets 10 movably inserted between said rails and said plates to enable the level of said plates to be adjusted to compensate for wear of the V-shaped grooves and of the V-shaped lower ends of the standards engaging therein, a 15 20 platen supported by said standards, grippers adapted to circulate round said platen, and means for causing said grippers to move alternately a short distance in one direction and a longer distance in the opposite direction.

25 In testimony whereof I have signed my name to this specification.

MAX HORA.
